UNITED STATES PATENT OFFICE.

FRANCIS H. BLATCH, OF HAZLETON, PENNSYLVANIA, ASSIGNOR TO ANTHRACITE SEPARATOR COMPANY, OF HAZLETON, PENNSYLVANIA.

ADJUSTABLE APPARATUS FOR FEEDING AND SEPARATING COAL AND LIKE MATERIALS.

Application filed November 4, 1920. Serial No. 421,644.

To all whom it may concern:

Be it known that I, FRANCIS H. BLATCH, a citizen of the United States, and resident of Hazleton, Pennsylvania, have invented **5** certain new and useful Improvements in Adjustable Apparatus for Feeding and Separating Coal and like Materials, of which the following is a specification.

This invention relates to means for feeding **10** coal and the like from a storage bin or hopper to any desired point, and is particularly designed for feeding coal (and the slate usually mixed therewith) to well known types of spiral separators.

15 Heretofore quantities of coal have been dumped directly on the fixed feed chutes leading to the spiral separator, often resulting in a rush of material over the separator with the result that it caused the coal to **20** push the slate off the separating threads into the coal thread. Or with loads of material having a preponderance of slate or rock, the coal would be held back so that it came too slowly with the result that it **25** would be carried off with the slate or refuse discharged.

The present invention aims to overcome these and other disadvantages of feeding the coal in large bulk. To these ends I have **30** provided a storage bin into which the coal cars can discharge their load and means for intermittently feeding small quantities of the material to the separator. And I have also provided means whereby the velocity at **35** which the material is fed to the separator can be varied so that the material will travel at the rate of speed to give the most efficient separation on a spiral separator of given pitch.

40 Further objects and advantages of my invention will be apparent from the following specifications when read in connection with the accompanying drawings in which—

Fig. 1 is a side elevation showing one embodiment of the invention;

Fig. 2 is a plan of a portion thereof on line 2—2 of Fig. 1;

Fig. 3 is a central longitudinal section through the storage bin, shaking table and **50** feeding chutes of the structure shown in Fig. 1;

Figs. 4, 5, 6 and 7 are views showing different installations constructed in accordance with the present invention, Fig. 6 be-

ing a horizontal section on line 6—6 of **55** Fig. 5.

Fig. 8 is a detail view showing the ridge plates of the separator in an adjusted position.

Referring first to Figs. 1 to 3, 10 represents a known form of spiral separator having multiple threads 11, 12 and 13 over which the material to be separated travels. As is well known in this art, pure coal is brighter and harder than the boney coal and **60** slate and, therefore, travels over the surface of the separator with less friction than the latter and travels in an outer path on the spiral runway and is discharged to a suitable receptacle. The slate and boney coal **65** travel on an inner path near the supporting post and are similarly discharged into a suitable receptacle. Adjustable ridge or division plates 14 similar to those shown in the Patent No. 1,197,057, granted to Frank **70** Pardee, September 5th, 1919, are provided near the discharge ends of the separator threads to direct the pure and impure coal **75** to their respective discharge chutes.

I provide improved means for adjusting **80** these ridge plates inwardly or outwardly, comprising a hand lever 14^a pivoted at 14^b to a fixed bracket and connected to the several ridge plates by suitable links 14^c so that they may all be moved simultaneously.

The ridge plates 14 are pivoted at 14^c to the surface of the runway and they are each connected by suitable pins 14^d with a bar **85** which is pivotally secured to the ends of the links 14^c. As thus arranged it is clear that **90** the several ridge plates can be simultaneously swung on their pivots so as to adjust them inwardly or outwardly.

A fixed plate 14^a having a plurality of **95** holes therein is provided to enable the operator to lock the ridge plates in the desired position by inserting the pin 14^e through a hole in the lever 14^a and into the registering hole in the plate 14^a. When necessary or desirable I may provide an individual hand **100** lever for each ridge plate.

To the upper end of the separator threads 11, 12 and 13, are pivoted feed chutes 15, 16 and 17. These chutes are adjustably held in position by means of a floating bar 18 to **105** which bar is connected a link 19, pivoted to a lever 20 which is adapted to be rocked about a fixed shaft 21 by means of a man-

ually operated link 22 having a plurality of holes 23 in the end thereof, through any one of which a pin 24 may be inserted to lock the link to a fixed post 25. This arrangement permits the operator to change the angle of inclination of the feed chutes 15, 16 and 17 so as to vary the velocity at which the material is delivered to the threads of the separator. As best shown in Fig. 2, the upper chute 15 is provided with discharge openings 26 and 27 through which the material is fed respectively to the chutes 16 and 17, which feed the two lower threads of the spiral separator. The upper thread receives that portion of the material fed thereto which passes around the sides of the openings 26 and 27 as indicated by the arrows in Fig. 2.

In order to overcome the objectionable practice of discharging a mine car load of coal at one operation to the separator, and then having the separator idle until such time as another car is brought into place and discharged, I employ a storage bin 30 of such capacity that a substantially continuous supply can be discharged therefrom. I also provide means for intermittently feeding a uniform volume of material to the separators, which means starts the material on its journey at a substantially uniform velocity. This prevents great quantities of coal from flowing to the separator in a mass and thereby preventing the ineffective separation due either to the too fast or too slow speed at which such a mass will travel and partially prevent the effective separation of the material. The storage bin is preferably, though not necessarily, formed with inclined walls 31 to guide the material toward the outlet neck 32, the lower end of which is open as at 33 and is provided also with a discharge orifice 34. The effective discharge area of the orifice 34 can be varied by means of a gate 35 operable by a lever 36 pivoted at 37 to a bracket on the storage bin and adapted to be moved by a control bar 38 and locked in its adjusted position by means of a pin 39 passing through one of the holes formed in the bar and engaging a suitable opening in a fixed bracket 41, as shown.

For intermittently delivering a substantially uniform quantity of material to the feed chutes, 15, 16 and 17 from the storage bin 30 at a constant speed, I employ a shaking table 40 having side guide flanges 42-42. The table being supported by angle bars 43 and 44, which are secured to flexible planks 45 and 46 which in turn are bolted to fixed girders 47 and 48. The table 40 is reciprocated by means of an eccentric 50, carried on a shaft 51, through an eccentric strap 52 and a connecting rod 53 which is secured at 54 to the underside of the table. The shaft 51 is journaled in suitable bear-

ings, not shown, which are mounted on fixed members in the mill in which the apparatus is installed. This shaft is driven by a pulley 55 from any suitable source of power. Secured to the upper side of the table 40 is a bar agitator 49 which when the table is reciprocated is adapted to enter the orifice 34 at the lower end of the storage bin so as to prevent the material from clogging or choking said discharge orifice.

The above described apparatus is for feeding material to a multiple thread separator having three threads, but it is to be understood that it can just as effectively be utilized for different types of separators and the arrangement of parts may be varied to suit different conditions and arrangements of installation in different mills. For example, in Fig. 4 is conventionally shown a separator 10^a having four separating threads and a corresponding number of adjustable feed chutes 15^a the inclinations of which can be varied by means of a link 22^a which rocks a lever 20^a which in this case straddles the bin 30^a and is pivoted directly thereto at 37^a. The table 40^a being reciprocated the same as above by an eccentric 50^a.

In Figs. 5 to 7 inclusive, I have illustrated an installation constructed in accordance with the present invention for supplying material to a pair of adjacent separators 10^b and 10^c, each of said separators having double separating threads 11^b and 12^c. With this arrangement the chief difference is that the pivoted feed chutes 15^b are formed so as to provide branches 15^c and 15^d leading respectively to the separators 10^b and 10^c. These chutes 15^b are adjusted by means of a lever 20^b pivoted at 21^b as shown. The storage bin is shaped somewhat differently, it being provided in this instance with an inclined bottom 31^b for discharging the material through the orifice 34^c, a gate 35^c being provided for varying the discharge area of this orifice. The lever 36^c for operating this gate is pivoted on the stud 37^c secured to the front wall of the bin 30^b. The eccentric 50^b for reciprocating the table 40^b is carried on a shaft 51^b which is located between the bin and the separators and is supported in bearings on a superstructure directly above the separators.

The agitator 49^c is curved near its end and projects upwardly into the orifice 34^c. The operation of each of the structures shown is practically the same and, therefore the following description will suffice for all.

The material to be treated is usually a mixture of coal and slate which has previously been separated on suitable screens according to size and dumped into the storage bin 30. The gate 35 is opened by means of the lever 36 and locked in position by the pin 39 so as to permit of a constant dis-

charge of the desired volume of material. The shaking chute 40 carrying the agitator 49 by its jogging movement causes the lumps of material to travel downward on its inclined surface and intermittently discharges it to the uppermost feed chute 15. Part of the material falls through the openings in the feed chute 15 to the lower chutes from which it is delivered to the corresponding thread of the separator to which it is attached. If the operator notices that the material is traveling at such a speed over the separator that an inefficient separation is being effected thereby, he can cut down this speed by lowering the free ends of the feed chutes. This adjustment being effected by manipulating the lever 20 through link 22 which can be locked in different positions by inserting pin 24 in different openings 23 in the bar. And in like manner if the volume of material is greater than desired, the area of the discharge orifice can be varied by manipulating the gate 35 through lever 36 and bar 38 which can be locked in position by the pin 39.

Heretofore, spiral separators have been fed from fixed feed chutes without provision for varying the velocity at which it entered the separator threads with the result that frequently slate traveling at an excessive speed would be pushed by the coal into the coal thread, and in other instances where there was a large percentage of slate and rock it would hold the coal back so that it would be carried off with the slate discharge. With my improved apparatus including the adjustable feed chutes and shaking table this disadvantage is overcome and these chutes can be adjusted so that a

given separator can efficiently handle the material coming from different coal veins. It being understood that the different veins contain different percentages of coal and refuse. The shaking table being driven by an eccentric effects intermittent discharge so that there is a time interval between each feeding impulse, thus the material is fed in desired quantities so that the volume reaching the separator at a given time is such that it will allow the lumps of material to spread apart with less interference from one another and will therefore permit of a very efficient co-action with the separator.

Though I have described with great particularly the specific embodiments illustrated herein, it is not to be construed that I am limited thereto, as it is clear that changes in arrangement and substitution of equivalents may be made by those skilled in the art without departing from the invention as defined in the appended claim.

What I claim is:

In an apparatus of the class described, the combination of a multiple thread spiral separator, separate inclined chutes for feeding the material to each thread of the separator and means for simultaneously adjusting the inclination of the feed chutes so as to vary the velocity at which the material is fed to the separator, certain of said inclined feed chutes having openings formed therein to permit the passage of material from an upper to a lower chute and a shaking table for intermittently feeding material to the uppermost chute.

In witness whereof, I have hereunto signed my name.

FRANCIS H. BLATCH.
